UNITED STATES PATENT OFFICE

2,491,657

SHOCKPROOF TRIPPING ARMATURE

Herbert C. Graves, Jr., West Chester, Pa., assignor
to I-T-E Circuit Breaker Company, Philadelphia, Pa., a corporation of Pennsylvania

Application May 28, 1943, Serial No. 488,841

8 Claims. (Cl. 200—109)

1

My present invention relates to circuit breakers and more particularly to tripping mechanisms therefor which are so arranged that while they may quickly respond to overcurrent or short circuit conditions of a predetermined nature, they will be ineffective to result in false tripping of the circuit breaker in the event of physical impact or shock.

More specifically, my invention provides means for absorbing the kinetic energy of a moving armature of a tripping mechanism where the movement of the armature has resulted from a sharp physical shock; and the arrangement of such means so that it will not impede movement of the armature in response to predetermined circuit conditions.

In the construction and operation of most circuit breakers, a movable contact arm is normally spring biased toward open position and is held in closed position where the movable contact is in current conducting relation with the stationary contact by a plurality of links or toggles, which in turn are supported by a latch. Movement of the latch to non-supporting position will thus permit the opening spring to be effective.

In circuit breakers of this type, a tripping mechanism is provided which will automatically operate the latch to non-supporting position upon the occurrence of predetermined circuit conditions.

Generally, such overcurrent devices include a series coil which energizes a magnet in accordance with the load conditions. An armature is arranged in such manner that it may be attracted by the magnet, but is normally biased away from the magnet. Upon the occurrence of such predetermined conditions, the armature is attracted to the magnet. The armature itself, or an abutment on the armature, is arranged so that when it is thus attracted some portion of the latching mechanism will be struck and moved to non-supporting position.

In order to obtain a quick response to overcurrent or short circuit conditions of predetermined intensity or duration, it is, of course, necessary that the armature be a relatively light member, the inertia of which may readily be overcome, so that it may move quickly.

The fact that the armature is very light is of no importance in ordinary stationarily mounted circuit breakers. Where, however, the circuit breaker is to be subject to sudden and extreme physical shocks or impacts, false operation of the armature may be induced by reason of such

2

shocks or impacts to cause the armature to move to trip the circuit breaker.

This problem is of utmost importance in the case of circuit breakers mounted on naval vessels.

Originally, circuit breakers intended to be used on naval vessels were designed with sufficient shock resistance to remain closed with some degree of consistency under conditions of broadsides fired by ships on which the circuit breakers were located. While such shock resisting arrangements might have tended to slow up the tripping operation of the circuit breaker, they nevertheless made it possible, under most such shock conditions, (arising from recoil of gun fire) to maintain the circuit breaker in closed position by reason of its inherent design.

The introduction of aerial warfare into naval combat has posed an entirely new problem in the design of circuit breakers suitable for combat vessels. It has been found that tremendous shocks, far exceeding a broadside shock, are imposed by near misses of bombs dropped from planes. The intensity of these shocks has resulted in a considerable modification in the design and test requirements of such devices, in order to assure their suitability for application on ships. The shock tests have been increased many fold over the old requirements. Materials and switchboard structures have been modified in the effort to prevent false tripping.

One of the essential elements which has been required to be modified, owing to this change in naval combat tactics, is the overcurrent feature of the circuit breakers.

Since previous circuit breaker structures were found unsuitable with respect to physical shocks of this kind, hold-in and lock-in devices were incorporated to prevent breakers from opening under conditions of shock. Many such hold-ins and lock-ins for preventing false tripping under shock conditions were designed actually to engage the latch or the armature and prevent any movement thereof while the hold-in or lock-in device was in operative position; other hold-in or lock-in devices have been designed to support the breaker mechanism links or toggles irrespective of movement of the latch.

It has been recognized, however, that hold-ins or lock-ins of this type, while of real importance and usefulness, were rather an immediate way of dealing with a pressing problem and were hazardous in that they prevented the automatic opening of the circuit breaker under short circuit conditions when the breakers were locked closed.

The primary object, therefore, of the present invention is the arrangement of the tripping armature of a circuit breaker, so that it will be readily responsive to selected overcurrent and short circuit conditions, while it will not be movable in response to physical shock conditions to a sufficient extent to trip the circuit breaker.

The ultimate desideratum is to produce a tripping mechanism which will be quick acting, will respond freely to circuit conditions; but which will not respond to physical shocks; in other words, one which will distinguish between circuit conditions to which it should respond and physical shocks to which it should not respond.

Several methods have previously been attempted in order to attain a result of this type. The oldest form consists of balancing the armature so as to prevent its operation on shocks from any direction. A proper balancing of the armature may actually result in preventing faulty operation or undesired operation under physical shock conditions. However, the balancing of the armature, as well as of its time delay sucker disc to produce a perfectly balanced system, increases the weight thereof and its inertia.

Also, when the armature is balanced, in addition to being heavier, it may still give faulty operation by virtue of a stop against which it must rest. This stop, working against one portion of the armature, may give it a rotational movement with reference to the pivot pin of the armature. That is, the physical shock to the vessel itself, resulting from a near miss of an aerial bomb, or a direct hit in some part will be transmitted to the stop, and from the stop will be transmitted with virtually ballistic force to the armature.

In any event, in a device having such a stop, rotational movement is bound to result as an incident of shock. This will necessarily result in movement of the armature, and its very inertia carries it through to trip the breaker.

My present invention overcomes all of these undesirable previously existing characteristics by latching the armature in an automatically releasable manner, so that:

1. The armature need not be balanced.
2. The weight of the time-delay sucker disc need not be counterbalanced.

3. The rotational impulse, given to the armature as a result of shock, does not result in tripping of the breaker.

4. The armature does not require counterbalancing and the resultant increase in inertia.

Essentially, my invention contemplates that the initial force of movement of the armature, owing to physical shock, be absorbed by causing it to strike against a movable but heavier mass.

Thus, while the armature may be given an initial almost ballistic movement by a physical shock and although, through its own inertia, it would then normally continue through to trip, a relatively heavy mass is interposed in its path of movement; and the work done by the armature in causing this mass to begin to move absorbs all of the energy of the moving armature, and causes it to come to rest while the interposed mass continues its movement. The interposed mass is arranged, however, so that its movement has no operational effect, that is the movement of the mass will not trip the breaker nor cause the armature to trip the breaker; and thus, this mass acts as a shock absorber.

The action, above described, is virtually the same as that which occurs when a billiard ball moving quickly strikes another ball and comes to a dead stop; while the other ball absorbs all

the energy of the first ball and is thus brought into rapid movement.

The physical shock to which a ship is subjected by a bomb or broadside impinges on the armature a force which, while it is considerably more intense than the pull exerted by its magnet, is of much shorter duration, being substantially instantaneous. On the other hand, the magnetic pull lasts as long as the short circuit or overcurrent condition exists. My novel structure thus, in effect, provides a time distinguishing characteristic responsive to the longer but less intense magnetic pull, but unresponsive to instantaneous physical shock.

It must here be borne in mind that the kind of physical shock thus guarded against is not so much the accelerating action of movement or heeling over of the ship as a whole, but rather the wave motion or vibration transmitted through the metallic structure of the vessel at a speed of the order of 16,000 feet per second and having a force directly proportionate to the impact. Thus should a bomb explode at or near one end of the ship, that impact will be transmitted through the metallic structure of the vessel to everything in contact therewith almost instantaneously and long before the ship as a whole begins to heel, swerve, skid, or otherwise move in response thereto.

Another and most important object of my invention, therefore, is the provision of means for absorbing the kinetic energy of a moving armature where the movement of the armature has resulted from a sharp physical shock.

Another and corollary object of my invention is the arrangement of such means so that it will be ineffective to prevent the complete movement of the armature in response to predetermined overcurrent or short circuit conditions.

A further object of my present invention is the arrangement of a circuit breaker armature and magnet in such manner that an additional mass is interposed in the path of movement of the armature toward the magnet, so that the armature must impart motion to this mass in the course of its movement toward the magnet.

Another object of my invention includes the arrangement of such mass in the path of movement of the armature to the magnet, so that the said physical mass will be effective to absorb the kinetic energy of the moving armature owing to a physical shock, but will not be effective to prevent the movement of the armature toward the magnet under conditions in which the magnet exerts a pull on the armature which exceeds a predetermined amount.

Another and more specific object of my invention is the provision of a rotatably mounted mass in the path of movement of the armature toward the magnet, wherein a portion of the armature will strike a portion of the rotatably mounted mass during the course of its movement to the magnet, and wherein the rotatably mounted mass will be brought into movement, and thereby exhaust all of the kinetic energy of the armature owing to the physical shock; but where the rotatable mass will continue to move out of the path of movement of the armature where a steady pull is exerted on the armature to a predetermined extent by the magnet.

Another and more specific object of my invention is the arrangement of such a physical mass so that it will be given a plurality of short motions in different directions in the course of the movement of the armature toward the magnet; so that in the event that the armature is brought into

movement by physical shock, the multi-directional movement of the mass will absorb the kinetic energy of the armature; while, under the influence of a steady pull of predetermined extent exerted by the magnet, this multi-direction movement of the mass will permit the armature to reach the magnet.

Another object of my invention is the provision of means for attaining proper sequential operation of main and subsidiary circuit breakers in the event of a short circuit condition in a subsidiary circuit.

These and many other objects of my invention will become apparent in the following description and drawings in which:

Figure 1 is somewhat schematic cross-sectional view of a circuit breaker showing the mounting thereon of a shock proof tripping unit of my invention, the circuit breaker being shown in the closed position.

Figure 2 is a view corresponding to that of Figure 1 showing the circuit breaker in tripped position at the moment that the armature has been fully attracted by the magnet.

Figure 3 is a side view of the overcurrent feature of the circuit breaker of Figure 1, showing the condition of the elements at rest and the armature in the non-tripping position.

Figure 4 is a view corresponding to that of Figure 3 showing the condition of the elements of Figure 3 under shock or physical impact conditions and demonstrating the manner in which the kinetic energy of the armature is absorbed by the rotatable mass interposed in the path of movement thereof.

Figure 5 is a view corresponding to that of Figure 3 and 4 showing the armature in fully attracted position to trip the circuit breaker, and demonstrating the manner in which the mass interposed in the path of movement of the armature may, when the armature is attracted by the magnet, be moved to a position which permits the armature to complete its tripping movement.

Figure 6 is an isometric view of the overcurrent device of Figures 3 to 5 showing the armature in non-tripping position.

Figure 7 is a front elevation view of the overcurrent feature in non-tripping position, taken from line 7—7 of Figure 1 looking in the direction of the arrows.

Figure 8 is a schematic representation of the principles involved in the absorption of the kinetic energy of the armature during its movement under physical shock conditions.

Figure 9 is a side view of a slightly modified form of shock absorbing armature construction showing the armature and associated elements in the at-rest position.

Figure 10 is a view corresponding to that of Figure 9 showing the armature of Figure 9 in the shock absorbing position.

Figure 11 is a view corresponding to that of Figures 9 and 10 showing the armature in the fully tripped position.

Figure 12 is a front view of the armature assembly.

Figure 13 is a side view of an additional modified form of shock absorbing arrangement for an overcurrent feature showing the armature and shock absorbing elements in the at-rest position.

Figure 14 is a view corresponding substantially to that of Figure 13 showing the arrangement of the elements of Figure 13 in the shock absorbing position.

Figure 15 is a side view corresponding to that of Figures 13 and 14 showing the arrangement of the elements thereof in the fully tripped position.

5 Figure 16 is a schematic side view of a modified form of overload feature showing the position of the elements in the at-rest position.

Figure 17 corresponds to that of Figure 16 and illustrates one shock absorbing position of the members of Figure 16.

Figure 18 corresponds to Figures 16 and 17 illustrating another shock absorbing position of the elements of Figures 16 and 17.

Figure 19 corresponds to Figures 16, 17 and 18 showing the fully tripped position of the members.

Figure 20 is an isometric view showing the relationship of the parts of the elements of Figures 16 to 20.

20 Figure 21 is a side view of a still further modified form of shock absorbing arrangement for the overcurrent feature showing the armature and shock absorbing elements in the at-rest position.

25 Figure 22 is a view corresponding to that of Figure 21 showing the arrangement of the elements of Figure 21 in shock absorbing position.

Figure 23 is a view corresponding to that of Figures 21 and 22 showing the arrangement of the elements in the fully tripped position.

30 Referring now to Figures 1 and 2, I have here shown somewhat schematically a typical form of circuit breaker in which my overcurrent feature is particularly useful. The circuit breaker itself forms no part of the present invention but is constructed and operates substantially in accordance with the disclosure of application Serial No. 332,037 of William M. Scott, Jr., now Patent 2,251,884, assigned to the assignee of the present invention.

35 However, a brief description of the operation of the circuit breaker will be useful in order fully to understand the function of the overcurrent feature of the present invention:

40 Figure 24 is a side view of the circuit breaker of Figures 1 and 2 comprising a back panel 20 through which is mounted the back connection studs 21 and 22. Current is led from the back connection stud 21 through the main stationary contact 23 to the main movable contact 24, then through the pigtail 25 to the terminal block 26, and then through the lower back connection stud 22. An overcurrent coil 30 is arranged to be energized by current passing through the lower back connection stud

55 22, and in turn energizes the magnet 31 of the overcurrent feature. The movable contact 24 is rotatably mounted at 35 on the movable contact carrying arm 36, which in turn is mounted on the contact bar 37. This contact bar is rotatable clockwise and counterclockwise on bearings (not shown), in order to cause the contact arm 36 to move between the closed and open positions of Figures 1 and 2.

60 An arm 40, rigidly secured to the contact carrying bar 37, is pivotally connected at its outer end to the link 42 which extends from the operating mechanism 43. Details of the operating mechanism are not here shown, but it is sufficient to note that the raising of the solenoid armature 70 44 will be effective to operate the operating mechanism to raise the link 42 to cause rotation of the movable contact carrying arm 36 from the position of Figure 2 to the position of Figure 1; or the handle member 45 may be effective to perform 75 the same operation.

Any suitable latch member may be utilized within the operating mechanism 43 to support the link 42 in the position of Figure 1. This latch may be so arranged that movement of the arm 47 from the position shown in Figure 1 to the position shown in Figure 2 will serve to trip the latch and thus remove support from the link 42.

The operating mechanism contained within the housing 43 may be of the type which is more fully described in detail in the application of Frank J. Pokorny, Ser. No. 339,682, now Patent 2,390,735, assigned to the assignee of the present invention.

The various other elements of the circuit breaker structure shown in Figures 1 and 2 are described in full detail in the applications above noted; and since the particular form of circuit breaker is no part of the present invention, and since the shock-proof overcurrent feature of the present invention may be applied to many types of circuit breakers, the details of the particular circuit breaker here shown will not be further described.

The entire overcurrent feature 50 of Figures 1 and 2 is more clearly shown in Figures 3 to 8 inclusive.

Figure 3 shows the overcurrent feature in a condition where the position of all of its elements correspond to the condition of Figure 1. The position of the elements of the overcurrent feature of Figure 5 corresponds to that of Figure 2.

Referring now to Figure 3, the armature comprises a member 60 of magnetizable material, preferably laminar in form, and mounted on the arms 61, which in turn are rotatable on the pin 62. A striking member 64, preferably one on each side of the armature, is also rotatably mounted on the pin 62. This striking member is integrated in any suitable manner with the armature member so that it will operate therewith as a single unit. In the construction here shown, this is achieved through a pin 65, carried by the armature-carrying arm 61, which passes through a suitable opening in an extending lug 66 of the striking member 64.

It will be clear from the various positions of the armature shown in Figures 3, 4, and 5 that the striking member 64 is essentially to be regarded as a part of or an extension of the armature movable therewith at all times. Thus, where the armature is moved from the at-rest or normal position of Figure 3 (hereinafter to be described) to the position of Figure 4 by a physical shock, the striking member moves therewith, as is clear from Figure 4; and when the armature is fully attracted to the tripping position, as shown in Figure 5, the striking member 64 also moves therewith.

A mass 70 is rotatably mounted on each side of the armature on the pin 71. The effectiveness of the mass 70, which is relatively great with respect to the mass of the armature 60 and its attached parts, may, where it is deemed desirable, be increased by mounting additional weight members 72 on the pin 71 and connecting these weight members to the mass 70 in any suitable manner as, for instance, by the bolts or rivets 73.

The striking member 64, in the embodiment here shown, is shaped somewhat in the manner of an escapement lock and is provided with an inwardly projecting abutment 75. The abutment 75 is so arranged that on rotation of the armature and striking member from the position shown in Figure 3 to the position shown in Figure 4 it will come squarely into contact with the abutting surface 76 on the rotatably mounted mass 70. This latter abutting surface 76 is defined by a lower

ledge 80 on the mass 70, which ledge, in its maximum counterclockwise position shown in Figure 3, provides just sufficient clearance for receiving the surface of the lower end 81 of the striking member 64. This surface 81 is curved on a radius r from the pin 62, and this radius is equal to the distance from the pin 62 to the lower edge of the abutment 76 of the mass 70 (when the elements are in the position of Figures 3 and 4); so that when the abutment 75 on the striking member 64 is rotated into contact with the abutment 76 on the mass 70, they will meet squarely, as shown in Figure 4. Likewise, the surface 80 of the mass 70 is so arranged that in the positions of Figures 3 and 4 all parts thereof will be at a distance greater than the radius r from 62-81, so that the surface 81 may clear the surface 80.

It will now be clear that in the event of a physical shock, which causes the armature 60 and its carrying arm 61 to rotate upwardly with respect to Figure 3, the striking member 64 will rotate in a clockwise direction with the armature. This simultaneous clockwise rotation of the striking member will result in the abutment 75 thereof striking against the abutment 76 of the mass 70. The torque in the rotating armature 60, its carrying arm 61, and the striking member 64 will thus be absorbed by the mass 70 and the additional weights 72 which are integral therewith. These latter members 70 and 72 will thus be brought into rotation and will fully absorb all of the kinetic energy of the members 60, 61 and 64.

Consequently, any physical shock or impact which will jar the armature into movement will cause the striking member to drive against the mass 70 and 72. The absorption of energy of movement of the armature with the transfer of this energy into rotational movement of the mass 70 and its weight 72 around the pin 71 will thus bring the armature 60 to a halt in the position of Figure 4 before it engages the tripping mechanism.

The armature 60 and its associated elements 61 and 64 will thus be restored to its normal position while the mass 70-72 moves. The angular movement of mass 70-72 and the speed thereof will depend, of course, on the comparative mass of members 70-72 with respect to the mass of members 60-61-64 and the initial speed originally imparted to the members 60-61-64.

In any event, the mere fact that the much greater mass 70-72 is brought into movement by the operation previously described will result in the halting of movement of the members 60-61-64.

The relative masses of the two members are such that this absorption of the kinetic energy of the moving armature is complete at the moment that the armature mass impacts mass 70-72 and the latter is brought into movement.

It will be understood, of course, that these movements are predicated on the fact that the shock which set the armature members in motion, while tremendous, is instantaneous; so that when the armature dissipates its kinetic energy in the mass 70-72, it no longer drives toward the trip position, but rather is restored to the normal position.

It is essential that the parts be so arranged that the very physical shock which brings the armature into movement will not be effective to move the mass 70-72 to a position where it will no longer block the movement of the armature.

Accordingly, the striking member 64 is provided on the side thereof opposite the abutment

75 with an extension 83, which extension (in the position of Figure 3) rests opposite the recessed surface 85 of the mass 70.

In the position of rest of Figure 3, the mean distance d from the center of pin 62 to the surface 85 is substantially equal to the radius r , while the space between the end 83 of the striking member 64 and the surface 85 is less than the height of the abutments 75 and 76. Consequently, under conditions of extreme physical shock, which may result not only in the movement of the armature but also in the simultaneous rotation of the mass 70—72, the rotation of the mass 70—72 is limited to a degree of movement equal to the space between surfaces 85 and 83. In other words, under extreme physical shock both members 64 and 70 may rotate, but the latter will not succeed in moving surface 83 out of the path of surface 85. Accordingly, the latter surface will strike against surface 83 stopping further movement of member 70; but since this degree of movement is not sufficient to cause a complete lack of registry of the abutments 75 and 76, then, on continued movement of member 64, the abutment 75 will still be in a position to strike against the abutment 76 in order that the mass 70—72 may absorb the shock of movement of the members 60—61—62.

As will be clear in Figure 4, however, when the abutment 75 strikes against the abutment 76, the extension 83 of the striking member has moved out of registry with the surface 85 of the mass and into a position where it is opposite the surface 90 of the mass, the latter surface being recessed from the surface 85. Here, a greater clearance is provided between the surface 90 and end 83 to permit rotation of the mass 70—72. This clearance is here shown as greater than the sum of the heights of the abutments 75 and 76.

Accordingly, when extreme physical shock occurs, even though the armature and the mass are simultaneously brought into movement, the mass is prevented from moving to a position where it will fail to absorb the impact of the armature until this actual impact occurs.

At the time of this impact, the members move to a position where the mass is free to rotate, so that rotative movement may be imparted to the mass so that it may, on the initiation of such rotation, absorb the shock of movement of the armature.

As will be obvious from Figures 3, 4, and 5, a latch engaging member 92 is rotatably mounted and rotatable with the pin 62. An adjusting screw 93, carried by the arm 61, bears against the surface 94 of the latch engaging member 92, so that when the armature 60 and its arm 61 rises, the latch engaging member 92 is caused to rotate in a clockwise direction.

As will be seen in Figure 3, the latch engaging member in the at-rest position of the overcurrent feature is completely out of engagement with the latch tripping arm 47.

In the position of Figure 4, where the shock absorbing condition is shown, it is clear that although the latch tripping member 92 has been rotated to some extent in a clockwise direction, it has not been rotated sufficiently to engage the latch tripping arm 47.

In the position shown in Figure 5, where the armature has been moved by magnetic pull to its full extent, the latch tripping member 92 has engaged the arm 47 and rotated the same sufficiently to result in a tripping operation.

As seen in Figures 6 and 7, the latch tripping

arm 92 is biased against the adjusting screw 93 by the coil spring 96, the center portion of which bears against the surface 97 of the latch tripping arm 92, and the ends of which bear against portions of the arms 61, the coil spring, of course, surrounding the pin 62. The coil spring is sufficiently strong, so that while it will yield under the influence of the rotation of the adjusting screw so that it may properly be adjusted with respect to the distance of member 92 from 47, it will not yield under the influence of an impact transmitted from the adjusting screw 93 to the base of the arm 92; so that to all intents and purposes (except for the provision for adjustment) the member 92 is integral with members 60—61—64.

Thus far, the shock absorbing aspect of the overcurrent feature has been described. It is, of course, essential that this shock absorbing arrangement be such that on actual selected circuit conditions the magnet 31, when energized, will be able nevertheless to attract the armature. This condition will be obvious from an inspection of Figures 4 and 5.

Figure 4 has thus far been described solely from the point of view of the shock absorbing aspect of the invention. However, Figure 4 represents an intermediate stage which occurs not only during movement of member 64 by shock but also during an overload condition where the magnet affirmatively and continuously attracts the armature 60. In this case, under such continuous attraction by the magnet 31, the armature 60 will rise so that the abutment 75 strikes against the abutment 76.

This movement is to be distinguished from the previously described operation where the armature rose only under a shock. In the latter case, the force of the shock was expended at the moment the mass was brought into movement, since the armature element, when striking the mass element, had only its own kinetic energy to give up. The absorption of this energy resulted in stopping the armature.

Under an overcurrent condition, on the other hand, the magnetic pull due to current conditions which causes the armature to rise is continuous during the rising of the armature and even after abutment 75 strikes abutment 76. Consequently, when the abutment 75 strikes the abutment 76, as shown in Figure 4, the energy which causes the armature to rise is not dissipated, and the pull of the magnet 31 nevertheless continues. Consequently, the abutment 75 bears with continuous pressure against the abutment 76 to rotate the mass 70 about its pivot 71 to the position shown in Figure 5, where the abutments 75 and 76 no longer engage each other. The armature is then free of mass 70 and continues to rise to the fully tripped position of Figure 5 where it may exert all its tripping power on trip lever 47 through lever 92. Here again, the curvature and surfaces of the various elements are important.

Thus, although theoretically it is possible that the surfaces 75 and 76 will separate and move from the position of Figure 4 to the position of Figure 5, when each of these surfaces is normal to their respective directions of movement at the time of impact, I have found from actual experiment that it is desirable to impart a slight slope to these surfaces, in order to permit them to slide with respect to each other from the position of Figure 4 to the position of Figure 5. This slope 75 has been shown in exaggerated form in the draw-

ings of Figures 3, 4, and 5, but is actually of the order of one or two degrees.

The surfaces 75 and 76 can, of course, move from the relative position of Figure 4 to the relative position of Figure 5 only if net components are in substantially opposite directions. That this condition exists, however, is obvious from an examination of the relative centers about which these abutments rotate. The abutment 75 rotates about the pin 62 under shock or overcurrent conditions in a clockwise direction. The abutment 76 rotates about the pin 71 under shock or overcurrent conditions in a clockwise direction. Since pin 71 is lower than pin 62 and to the left thereof (with respect to Figures 3, 4, and 5), then the continuous movement of these abutments will result in abutment 75 rising and abutment 76 dropping. This actually occurs as is shown by a comparison of Figures 4 and 5.

Accordingly, during overcurrent conditions where the armature 60 is continuously attracted by the magnet 31, the abutment 75 is brought against the abutment 76; and under the continuous rotational movement imparted to the abutment 75 by the magnet and armature, it continues to slide off abutment 76, pushing abutment 76 downwardly until the surface 81 rides up onto the ledge 100. When the surface 81 thus comes into contact with the ledge 100 there is no further impediment to the movement of abutment 75, and consequently the armature 60 may now rise to the pole of magnet 31, thus tripping the latch. The addition of the shockproof feature to the tripping armature nevertheless results in substantially no appreciable time delay in actual tripping under overcurrent conditions, although, if desired, a time delay may be secured. Under such overcurrent the armature is attracted so that the abutment 75 strikes the abutment 76; and under the continuous pull of the magnet on the armature the abutment 75 simply slides up with respect to abutment 76, and thus rotates the mass 70 out of the way to permit the armature to be moved to full trip position. The slope of abutments 75 and 76 permits this easy separation to occur.

It will be obvious, of course, that the slight slope, previously mentioned, which is given to the abutments 75 and 76, should be only just sufficient to permit the members to slide apart under the influence of a continuous pull exerted by the magnet. It has been found that this result may be achieved, as above pointed out, by a slope of the order of one or two degrees to the axis of movement of the abutment 75 at the time it strikes the abutment 76.

In Figures 6 and 7, the actual practical physical embodiment of the structures herein described is shown.

Side plates 110 serve as a housing for the armature and shock absorbing features. Additional L-shaped plates 111 are secured to flanges 112 of the side plates in order to provide additional support for the pins 71 which have been described. Upper flanges 113 on the side plates provide means for securely mounting the magnet 31 with respect to the armature. The armature 60 is carried by the arms 61 which are rotatable about the pin 62; the pin 62 is provided with extensions 115 of reduced diameter extending through openings in the side plates; cotter pins 116 serve to secure the pin in position. Pin 65 is simply for the purpose, previously described, of integrating the striking member 64 with the armature 60 and its arms 61. This pin, as is obvious from Figure

6, is carried by the arms 61 and extends through openings in the lug 66 and the striking member 64.

Since it is desired that all of the weight be in the mass 70 and its associated weights 72, rather than in the armature and its associated members, the arms 61 are only sufficiently heavy to provide an appropriate support for the armature 60; and the striking member 64 has an opening 120 in order to decrease its weight. Of course, all of these members must, however, be sufficiently strong to withstand the shocks which are to be anticipated.

Each mass 70 on each side is rotatable on the pin 71 which is mounted in suitable openings in plates 111 and 110 on each side. The additional weights 72, which increase the mass of the member 70, are mounted on each side thereof. As shown in Figure 7, these weights are spaced apart sufficiently to permit the striking member 64 to move freely therebetween.

Spacer members 122 of sufficient width may be mounted on the pins 76 between the plates 110 and the weights 72, in order to ensure proper registry between the striking member 64 and the mass 70.

A tension spring 130 may be provided at each side connected at one end to a pin 131 carried by a weight 72, and at the other end to a lug 132 carried by the plate 111 in order to return the mass 70—72 to the rest position of Figures 3 and 6. This spring need exert only sufficient force to return the members to the position shown and is not maintained primarily for use as a shock absorbing element, since shock absorption takes place, as above described, by reason of the fact that all of the kinetic energy of a smaller mass is absorbed when it strikes the larger mass and causes the larger mass to move.

The at-rest position of the weights of Figures 3 and 6 may be determined by the fact that the end 140 of the weights 72 bear against the lower reentrant flange 141 of the vertical plates 111. The at-rest position of the armature is determined by any suitable stop or by any time-delay element, such as a dashpot, which is connected thereto.

As will now be obvious, my invention applies D'Alembert's principle of inertia reaction of a mass; i. e., that the energy of movement of a light mass may be imparted to a heavy mass to cause it to take up all the motion of the first mass. The relative masses may, of course, be greatly disparate, but this is limited, however, by the fact that the armature and its associated members must be sufficiently heavy to have sufficient strength for withstanding the physical shocks; and the larger mass must be sufficiently small so that it can be rotated by the armature and be enclosed in a relatively small housing, so that the size of the circuit breaker need not be increased thereby or the elements of the circuit breaker be disarranged.

This limitation, however, may be overcome by the relative arrangement of the parts, as shown in Figures 3 to 5, wherein the abutment 75 is at a relatively great distance from the center of movement of the members 60—61—64, and thus has relatively little leverage, while the abutment 76 of the mass 70 is relatively close to the center of rotation 71.

As a matter of fact, the abutment 75 is so arranged that it moves around the center 62 and just under the center 71.

This relative arrangement of the radial distances of the respective striking abutments from

their respective centers of rotation multiplies the effective mass of the members 70-72 and dispenses with the necessity for using relatively large masses to effect shock absorption.

In Figure 8 I have shown in very schematic form the effect of this displacement of the abutments from their centers of rotation.

The member 64' of Figure 8 corresponds roughly to the striking member 64; the gear teeth 75' correspond roughly to the abutment 75; the pinion 70' corresponds roughly to the mass 70; while the weight 72', secured to the pinion 70', corresponds roughly to the additional weights 72 carried by the mass.

Here it will be seen that any movement imparted to the member 64' resulting in rotation of the pinion 70' and the mass 72' will be at a greater mechanical disadvantage with respect to the mass 72' so that the mass 72' has been effectively multiplied. This essentially is the condition which is obtained by arranging the members of Figures 3 to 7 so that the abutment 75 is relatively much further from its center of rotation than is the abutment 76.

In the foregoing, I have described a shock-proof armature which will be inoperative to trip a circuit breaker on the occurrence of an extreme physical shock, even though it will be readily operable on the occurrence of overcurrent conditions to effect a tripping operation.

The principle involved is, as above pointed out, similar to that of a billiard ball moving rapidly over the surface of a table, striking another billiard ball, and immediately coming to rest while it imparts movement to the second ball.

By the means described, it becomes feasible completely to dispense with hold-in and lock-in features and the attendant difficulties thereof which have been previously described.

While hold-in or lock-in features may be and are useful and important, where, for some unusual reason, it is necessary to maintain a circuit breaker closed, irrespective of current conditions, and while they are necessary as attachments to circuit breakers which have already been designed and built, the present invention is designed primarily to make such hold-in or lock-in elements unnecessary.

As above pointed out, the immediate reaction to the discovery that the severe physical impact of near misses of aerial bombs resulting in virtually unpredictable forces was to provide schemes for definitely locking the circuit breaker so that it could not react to such forces; and thus resulted in the development of positive hold-ins and lock-ins. The present invention is designed to obviate substantially all necessity for such hold-ins or lock-in features and to provide a suitable shock-absorbing element which adds no substantial weight to the armature and which will positively prevent false operation of the armature under physical impact. The shock-proof element herein disclosed will not interfere but rather will aid proper sequential operation of circuit breakers.

In the proper arrangement of circuits on battleships, as well as elsewhere, it is desirable to arrange the circuit interrupters so that in the event of overcurrent or short circuit on a subsidiary line, the circuit breaker protecting that line will trip before any of the circuit breakers protecting the main lines. Thus, for proper sequential operation, a circuit breaker protecting a particular piece of equipment should trip before the circuit breaker protecting a plurality of lines to similar pieces of equipment. This latter circuit

breaker should trip before the circuit breaker which protects the main line; this is important so that a fault in any subsidiary piece of equipment will not render the entire network of main and subsidiary lines inoperative.

A short circuit in a subsidiary line resulting in a rapidly increasing tremendous overcurrent normally will tend to cause all of the armatures in all of the circuit breakers to begin to move. Owing to the tremendous short circuit capacity of the generators on battleships today, all of the armatures tend to become substantially instantaneous; and the initial movement given to these armatures under such overcurrent (while perhaps not as great as that which would be imparted thereto under the physical shock of an aerial bomb) is relatively very great.

Consequently, even though the armature of the circuit breaker protecting the faulty piece of equipment trips the circuit breaker, the armatures of the more important circuit breakers may, because of their inertia, follow through to complete a tripping operation. This may occur in spite of the fact that the excess magnetic attraction has ceased because the circuit breaker protecting the faulty piece of equipment has interrupted the short circuit.

However, the interposition of the energy absorbing element in the path of movement of each of the armatures ensures that should the overcurrent condition be cleared by interruption of the subsidiary breaker before the armature of the main breaker has removed its mass from its path to complete a tripping operation, the inertia energy of movement of this armature will be fully absorbed by its associated mass and will not follow-through to trip. This will be particularly true where the armatures of the main breakers are comparatively heavier than the armatures of the subsidiary breakers so that they will begin to move an instant later.

I have also found that where it is desirable to use extremely light members, or where it is desirable positively to limit the armature against false tripping movement under physical shock conditions, the surfaces 83 and 85 (Figure 3) may be sloped to effect this result. Thus, surface 83 of striking member 64 may be sloped at an angle to the radian d so that when the said surface 83 is subjected to a force having a vector substantially perpendicular thereto, striking member 64 and its associated armature would be subjected to a counterclockwise rotative force around pin 62. With respect to the showing of Figure 3, such a slope, although it may be relatively slight, would make surface 83 more nearly vertical.

Surface 85 of mass 70 may then be correspondingly sloped, so that when it strikes surface 83 it will impart to it the counterclockwise rotative force above mentioned.

Now, should a physical shock occur, imparting clockwise movement to the armature and the striking member 64 in the manner previously described, and at the same time imparting a clockwise movement to mass 70 also in the manner previously described; then the sloped surfaces 83 and 85 will be brought into violent contact. The slope of these surfaces would then immediately impart a counterclockwise rotative force to the striking member 64 and its armature to cause it to rebound and prevent a false tripping operation.

The degree of counterclockwise force thus imparted depends of course on the slope of surfaces 83 and 85. A relatively slight slope of the order of five-ten degrees will absorb the clockwise ro-

tation of the armature under physical shock and drive it back. A greater slope will positively absorb any force which may be imparted to the armature. A lesser slope will absorb the rotative force of the armature in virtually every instance; but the abutments 75 and 76 serve as a positive safety factor in the event such absorption does not occur.

By this means a definite cam action is provided to return the armature to its original position under shock. Under condition of violent shock, the movement of the armature is at extremely high speed; and this positive return action, made possible by sloping of surfaces 83 and 85 becomes important, since the members may oscillate several times in their limited movement.

The same basic principle applies where surfaces 83 and 85 are sloped as where surfaces 83 and 85 are not sloped. The energy of movement of the armature is absorbed by the mass 70; and the armature, after imparting all its energy to the mass 70 is immediately brought to a stop. Where surfaces 83 and 85 are sloped, however, the kinetic energy of the mass 70 is also utilized to increase the degree and speed of absorption of the energy of the armature and to positively drive the armature back.

Such sloping of surfaces 83 and 85 will not however interfere with a tripping operation where magnet 31 is energized sufficiently to attract the armature. In this instance, surfaces 83 and 85 would not ordinarily be brought into contact; but, if they are, the continued attraction by the magnet which applies a positive continued rotative movement to the armature (while mass 70 is not subjected to any such continuous movement) will enable the armature to move the mass out of the way to enable it to trip.

The principles heretofore set forth in connection with Figures 1 to 8 may, of course, be applied in many modified forms to various types of structures, all following substantially the same principle.

In Figures 9 to 12 I have shown one such modified form which utilizes substantially the same elements. In this form, the overcurrent magnet 231 is supported in any suitable manner in the housing 200. An armature 260 is rotatably mounted on pin 262 and may be attracted by the magnet 231. The armature 260 and the magnet 231 are of a well-known type and require no further description. It is sufficient to point out, however, that the adjusting screw 293 on the armature when it is attracted will strike against the arm 247 and will cause this arm to trip.

The striking member 264 is centrally located, as shown in Figure 12, with respect to the armature and extends beyond the pin 262. As has previously been pointed out, it is essential that the striking member be integrated with the armature. Consequently, the striking member 264 has an extension 264a within the laminations of the armature through which the rivets 261, which secure together laminations of the armature, pass.

A mass 270 is rotatable on the pin 271 and has secured thereto additional weights 272 on either side which are also rotatable on the pin 271, these weights 272 being integrated with the mass 270 by the pins 273 which pass through the weights and the mass. Consequently, the members 270-272 form a single integral rotatable weight which operates in substantially the manner previously described.

The striking member 264 is again of escapement formation and has an extension 281 provided with an abutment 275. This abutment may

bear against the abutment pin 276 of the mass 270-272. The abutment pin 276, instead of being a specific part of member 270, as in the previous case, is simply a pin securely mounted between opposite plates 272.

Should a physical shock imparted to the armature cause it to move toward the magnet, then, as shown in Figure 10, the abutment 275 will strike the abutment pin 276; and thus the kinetic energy of the moving armature will be absorbed by the mass 270-272 which will then rotate. Since all of the moving energy of the armature will thus be transmitted to the mass 270-272, the armature will have no further moment toward the magnet, and a tripping operation will not occur.

Here again, the member 270 is so arranged that should it rotate under physical shock, such rotation will be prevented in the first instance by the ledge 285 of the member 270 bearing against the extension 283 of the striking member 264. Consequently, the mass 270-272 cannot under a physical shock rotate into a position where it cannot be engaged by the armature until the armature itself has struck the mass and initiated its movement.

When, as shown in Figure 10, the abutment 275 of the striking member 264 strikes the abutment pin 276 of the mass, then the extension 283 of the striking member moves opposite the recess 290 so that the mass may now rotate. The fact that the surface 290 may now strike against the extension 283 does not interfere with the operation of the shock absorber. All of the moving energy of the armature is absorbed when the mass 270-272 begins to rotate. Consequently, the armature will normally fall back.

The striking of surface 290 against the extension 283 will have the additional effect of causing the armature to snap back from the position of Figure 10 to the position of Figure 9.

As previously described, should an overcurrent occur where the magnet attracts the armature, then the armature will first move from the position of Figure 9 to the position of Figure 10; but, owing to the fact that the energy of movement of the armature is not dissipated at this time, but rather the magnet still remains energized to continue to attract the armature and the effective force of the magnet has been increased owing to the greater proximity of the armature, the abutment pin 275 will now push on the abutment 276, pushing it out of the way, as shown in Fig. 11, so that the armature may reach the magnet.

The operation of the shock absorbing overcurrent feature of Figures 9 to 12 thus follows exactly the principles described in connection with Figures 1 to 8 and requires here no further elaboration.

It is sufficient to point out, however, that, as seen in Figure 12, the weights 272 are greatly increased, and the armature is relatively lighter. The weight of the striking member 264 is substantially decreased by the curved recess 295. The weight 270-272 is maintained in the at-rest position of Figure 9 by the tension spring 230 which biases the member 270 to a position where its surface 280 bears against the extension 281. The spring 230 is simply a resetting spring and for purposes of the present invention should not be regarded as having any shock absorbing value.

The responsiveness of the armature to overcurrent conditions may be varied by the adjustable tension spring 220, Fig. 11, which at one end is secured to the armature and at the other end is secured to a slide member 221 threaded on the

vertical adjusting screw 222, which is mounted for rotatable movement only in the bearings 223, 224.

The pin 262, which supports the armature, and the pin 271, which supports the weights, are carried between the side plates 210 of the housing and are held in place by appropriate cotter pins 216.

The operation of this overload feature is exactly similar to that which has been previously described in connection with Figures 1 to 8.

In the present case, the abutment 275 of the striking member 264 should (in Figure 10) move into engagement with the abutment pin 276 along a line which is substantially an extension of a radius thereof. There would be no substantial impediment to the attraction of the armature by the magnet while the armature moves from the position of Figure 10 to the position of Figure 11. The abutment 275 may however be made to strike the pin 276 along a line which is one or two degrees to the right of a radius parallel to the path of movement of the abutment 275. Such slight displacement by one degree will not interfere with the shock transmitting character of the operation when abutment 275 strikes pin 276; but will, when the magnet attracts the armature, permit the abutment 275 readily to displace the pin 276 and slide over the same, as shown in Figure 11, to result in tripping the circuit breaker.

The armature may be provided with a suitable time delay element, preferably, one which effects a time delay under relatively low overcurrent conditions, but is instantaneous under high overcurrents or short circuits.

In Fig. 10, I have shown a dashpot 210 secured to the housing of the overcurrent feature and having a tubular member 211 connected by pin 212 to the armature. The tubular member contains a compression spring, the lower end of which bears against the base of the tube and the upper end of which bears against the adjusting nut 215. Nut 215 is mounted on link 213 which passes through an opening in the base of the tube and is connected to the sucker disc 214 of the dashpot.

The compression spring is adjusted so that, at overcurrent conditions of predetermined maximum intensity, it is substantially uncompressible and thus acts as a rigid member connecting sucker disc 214 and link 213 to the tube 211 which is connected to the armature. The time delay afforded by the dashpot is thus obtained.

But the compression spring is so adjusted that under short circuit conditions or excessive overcurrent conditions, the attraction of the magnet by the armature will be sufficient to compress the spring. Under such conditions, the armature pulling on the tube 211 will draw it up, compressing the spring between the base of the tube and the nut 215 on link 213. Accordingly, the armature may then respond instantaneously irrespective of the time delay for which sucker disc 214 is adjusted.

Many other modifications of the basic principles herein described should now be obvious.

One additional such modified form is shown in Figures 13, 14, and 15 where, however, substantially the same basic principles are applied.

In Figure 13 I have shown an armature 360 which is rotatably mounted on the pin 362 and which is arranged to be attracted by the magnet 331 under overcurrent conditions. The magnet 331 is energized in any suitable manner as, for

instance, by the coil 330. This armature and magnet arrangement is well known and requires no further description. It is obvious, however, that when the adjustable screw 393 on the armature strikes the tripping arm 347, the latch in the operating mechanism may be released on rotation of arm 347 to open the circuit breaker.

A weight 370 is also rotatably mounted on pin 362; such weight may, of course, be mounted on either side of the armature and may be symmetrically arranged in such manner that any weight 370 may interchangeably be used on the right or left side. The weight is also by this means perfectly balanced and thus should not rotate on the occurrence of a shock. The weight is provided with a recess 380 defining an abutting surface 376. The armature is provided with an abutment pin 375.

Should a physical shock cause the armature 360 to rise, then the pin 375 thereof will, as shown in Figure 14, strike the abutting surface 376 of the weight, thus imparting all of the energy of the armature to the weight 370 and causing the same to rotate. The kinetic energy of the armature will thus be absorbed at the moment the movement thereof is imparted to the weight 370 and the weight 370 begins to rotate.

The weight 370 is so mounted with respect to the base 311 of the housing that the end 340 thereof will strike the base 311 of the housing before the surface 390 within the recess 380 can strike the pin 375. Accordingly, the weight 370 cannot follow through so that the surface 390 thereof, hitting the pin 375, would strike the armature 360 to urge it into tripping position. By this means also shock absorption is achieved in accordance with the principles already set forth.

In the event of an overcurrent resulting in appropriate energization of the magnet to attract the armature, the armature 360 will first move from the position of Figure 13 to the position of Figure 14. Since the magnet, however, is energized and the armature is thus continuously attracted after the armature has come into contact with the weight 370, the continuously applied force will place the weight 370 in motion and the armature will continue to move to a point where all of the parts assume the position shown in Figure 15 and the tripping arm 347 is contacted. Here again, all of the principles previously described apply and need no further elucidation.

The at-rest position of the weight 370 is maintained by the tension spring 382 connected at one end to a pin 383 of the weight and at the other end to a bolt 384 of the housing. The stud 386, cushioned by compression spring 385, will act as a shock absorber when the mass 370 falls back after having absorbed the shock.

Many other modifications of my shock-absorbing device utilizing the same principles are possible. Thus, for instance, in Figures 16 to 20 I have shown one further such modification where the weight is given a multi-directional movement to effect shock absorption.

In these figures an overcurrent magnet 431 is arranged to attract an armature 430 which is mounted on the arms 461, which in turn are rotatable about the pin 462. The tripping element 492 of the armature and the operation thereof corresponds exactly to the tripping element 92 of Figures 1 to 8 and is arranged to engage the tripping arm 447 of the operating mechanism when the armature has been fully attracted.

Armature 460 is provided with a pair of extending arms 464 which between them support a striking pin 475. A weight 470 is mounted for rotation in either direction on a pin 471. The striking pin 475 passes through the zig-zag vertical slot 480 in the weight 470.

When the armature is at rest, the position of all of the elements is that shown in Figure 16.

Should a physical shock be imparted to the armature causing the same to rise, then, as shown in Figure 17, the striking pin 475 will strike against the abutting surface 476 within the zig-zag slot 480. Since the abutting surface 476 is in this case at a substantial angle to the direction of movement of the pin 475, the weight 470 will immediately rotate to the position shown in Figure 18 where the surface 485 of the slot will strike the pin 475.

The kinetic energy movement of the armature, owing to physical shock, should be absorbed immediately upon the beginning of movement of the weight 470 from the position of Figure 17 to the position of Figure 18; and the armature will no longer continue to rise toward the magnet 431; and the members will fall back to the position of Figure 16.

Should there, however, be any residual energy left in the armature after the pin 475 strikes surface 476, then the striking of surface 485 against the pin 475 should serve to absorb this further energy. However, should there be even further residual energy in the armature, then, when the pin 475 strikes against surface 490 within the slot, additional rotational movement will be imparted to the weight 470 in an opposite direction thus absorbing all of the kinetic energy of the armature.

In most cases, all of the kinetic energy of the armature will be absorbed when the pin 475 strikes surface 476 within the slot, and the further slight rotation movement imparted to the weight 470 will be sufficient to halt the movement of the armature. The rotational movement thus imparted to the weight 470 is itself absorbed when the surface 485 thereof comes into contact with the pin 475. Should there now be any residual movement within the weight 470 or in the armature 460, all of this residual movement will be absorbed when the pin 475 strikes surface 490. In this case, the movement of the weight in one direction must be completely reversed, thus absorbing all of the energy of movement of both the weight and the armature; and the armature and weight will then drop back to the position of Figure 16.

In the event, however, that the magnet is energized under overcurrent or short circuit conditions to attract the armature, then, even after the pin 475 strikes surface 476, the continued energization of the magnet will continue to draw the armature up so that the weight will oscillate back and forth as the armature rises from the position of Figure 16 to that of Figures 17 and 18 to the tripped position of Figure 19. Here again, the principles previously described are completely applicable. In this case, as well, the full energy of movement of the armature should be absorbed when the weight begins to move. However, the fact that the weight must oscillate back and forth as the armature rises ensures that the moving energy of the armature is completely absorbed.

In Figures 21, 22, and 23, I have shown a

modification of the construction of Figures 13, 14, and 15 wherein the shock absorbing element is in contact with the armature in the at-rest position but serves to absorb any shock transmitted to the armature.

In Figure 21 I have shown an armature 560 which is rotatably mounted on the pin 562 and is adapted to be attracted by magnet 531 under overcurrent conditions. This magnet is energized in any suitable manner as, for instance, by the coil 530.

The armature and magnet arrangement correspond substantially to that of Figures 13 to 15; and the operation wherein the adjustable screw 15 593 strikes the tripping arm 547, and the resultant release of the tripping mechanism of the circuit breaker also corresponds to that described in connection with Figures 13 to 15.

Weight 570 is also rotatably mounted on pin 20 562. A similar weight may be mounted on opposite sides of the armature and may, if desired, be symmetrically arranged so that weights may be interchangeably used on either side. The weight is also symmetrically balanced around 25 the pivot point 562 so that it itself is substantially shock-proof.

Weight 570 is provided with a recess 580 defining an abutting surface 576 which bears against the abutment pin 575 of the armature 30 560. Should a physical shock for any reason be transmitted to the armature 560, then this shock through the abutment pin 575 will be transmitted to the abutting surface 576 and hence to the weight 570.

35 The movement of the armature 560 in consequence of the shock will thus be transmitted to the weight 570, and the kinetic energy of movement of the armature will thus be immediately imparted to the weight 570 so that the weight 40 will rotate from the position shown in Figure 21 to the position shown in Figure 22.

Owing to the fact that the kinetic energy of movement of the armature 560 is thus absorbed by the bringing of the weight 570 into movement, 45 the armature 560 will move only slightly and will come to a stop, as shown in Figure 22, while the weight 570 continues to move.

Weight 570 is so mounted with respect to the base 511 of the housing that the end 540 thereof 50 will strike the said base before the surface 590 of the recess 580 can strike pin 575.

Accordingly, weight 570 will not follow through to push the armature upward. By this means, 55 the shock transmitted to the armature will be transmitted to the weight 570 and absorbed by the movement thereof.

In the event of an overcurrent resulting in energization of magnet 531, the armature 560, 60 under the continuously applied force of the magnet, will move from the position shown in Figure 21 to the position shown in Figure 23. The continuously applied force of the magnet will in such case be sufficient to rotate not merely the armature but the weight itself.

The at-rest position of weight 570 is maintained by the tension spring 582 connected at one end to a pin 583 of the weight, and at the other end to a bolt 584 of the housing.

70 In various experiments and tests which have been made with these various modifications, I have found that the construction shown in Figures 1 to 8 is at present the preferred form. Its efficiency is such that in some instances it may be perfectly feasible to dispense with part or all

of the additional weights 72 and to rely entirely on the member 70.

The basic principles described in connection with Figures 1 to 8 are present in all of the other modifications. The essential element is that kinetic energy of movement of the armature, as a result of physical shock, is imparted to a mass, which may be greater or which is at a mechanical advantage with respect to the armature and its parts; and the initiation of movement of this greater mass absorbs all of the kinetic energy of the armature, so that the armature no longer continues to rise under the influence of such shock.

Also, the arrangement of the shock absorbing member is such that under overload conditions, it will be automatically moved out of the way without creating any appreciable delays in the response of the armature, so that the armature may move through its full cycle to trip the circuit breaker open under overload or short circuit conditions.

In the foregoing, I have described my invention in several modifications which are to be regarded as merely illustrative of the basic principles involved.

Many other modifications and variations of my invention should now be obvious to those skilled in the art without departing from the spirit thereof. Accordingly, I prefer to be bound not by the specific disclosure herein, but only by the appended claims.

I claim:

1. A trip device for a circuit breaker comprising a trip member movable to cause opening of the circuit breaker, means comprising a movable mass having a plurality of projections, one of said projections being in the path of movement of said trip member, said mass being set in motion by impact with said trip member in response to a jarring force, and said mass when in motion impinging another of said projections on said trip member to prevent movement of said trip member in opening direction and extent sufficient to cause opening of the circuit breaker.

2. In a circuit breaker, a magnet having a pivoted armature, a striking member secured to and movable with said armature and having an abutment on one side thereof and an extension on the other side thereof, a pivoted mass having a recessed surface opposite said extension, an abutment opposite said abutment on said striking member, the mean distance from the center of the pivot of said striking member to said recessed surface on said mass being substantially equal to the distance from said pivot to the end of said abutment on said striking member and the distance between the end of said extension on said striking member and said recessed surface on said mass being less than the height of the abutments on said mass and said striking member and the mass being pivoted at a point so that the rotation of said mass is limited to a degree of movement equal to the space between said extension on said striking member and said recess on said mass, which degree of movement is less than sufficient to move said extension out of the path of said recess whereby said surface and recess will engage and stop further movement of said striking member of said mass before said abutments disengage, and said mass will absorb the shock of movement of said striking member, the surfaces of said extension and recess being sloped at an angle to the radius to said pivot of said striking member so that when said sur-

face extension is engaged by said recess, it is subjected to a force having a vector substantially perpendicular to the radius and the striking member will be subjected to a rotated force in the opposite direction from said shock.

3. In a circuit breaker, a magnet having a pivoted member operable about its pivot in response to the energization of said magnet and also operable about its pivot in response to a shock, a pivoted mass having a surface in the path of movement of said member and engageable by said member when said member moves about its pivot in response to shock, said member having a surface in the path of movement of said mass when said mass moves in response to impact from said member, for limiting movement of said mass.

4. In a circuit breaker a magnet having a

1. In a circuit breaker, a magnet having a pivoted member operable about its pivot in response to the energization of said magnet and also operable about its pivot in response to a

shock, a pivoted mass having a surface in the path of movement of said member and engageable by said member when said member moves.

25. about its pivot in response to shock, said member having a surface in the path of movement of said mass when said mass moves in response to impact

from said member, for limiting movement of said mass to maintain said mass in the path of movement of said member and limit movement of said

5. In a circuit breaker, a magnet having a pivoted member operable about its pivot in re-

35 pivoted member operable about its pivot in response to the energization of said magnet and also operable about its pivot in response to a shock, a pivoted mass having a surface in the path of movement of said member and engageable by said member when said member moves about its pivot in response to shock, said member
40 having a surface in the path of movement of said mass when said mass moves in response to impact from said member, for limiting movement of said mass to maintain said mass in the path of movement of said member and limit

45 path of movement of said member and limit movement of said member, said mass having a recess, which, when said member is moved in response to the energization of said magnet and in turn moves said mass with said member, permits said mass to be moved out of the path of 50 movement of said member to permit movement of said member beyond said previously mentioned limit of movement of said member.

6. In a circuit breaker, a magnet having a pivoted armature, a striking member secured to 55 and movable with said armature and having an abutment on one side thereof and an extension on the other side thereof, a pivoted mass having a recessed surface opposite said extension, an abutment opposite said abutment on said striking 60 member, the mean distance from the center of the pivot of said striking member to said

the pivot of said striking member to said recessed surface on said mass being substantially equal to the distance from said pivot to the end of said abutment on said striking member and the dis-

65 distance between the end of said extension on said striking member and said recessed surface on said mass being less than the height of the abut-

70 said mass being less than the height of the abutments on said mass and said striking member and the mass being pivoted at a point so that the rotation of said mass is limited to a degree of movement equal to the space between said extension on said striking member and said recess on said mass, which degree of movement is less than sufficient to move said extension out of the 75 path of said recess whereby said surface and

recess will engage and stop further movement of said striking member of said mass before said abutments disengage, and said mass will absorb the shock of movement of said striking member.

7. In a circuit breaker, a magnet having a pivoted armature, a striking member secured to and movable with said armature and having an abutment on one side thereof and an extension on the other side thereof, a pivoted mass having a recessed surface opposite said extension, an abutment opposite said abutment on said striking member, said abutment on said mass being in the path of movement of said striking member when said striking member is moved by shock for transferring the energy from said member to said mass, said extension on said striking member being in the path of movement of said mass.

8. In a circuit breaker, a magnet having a pivoted armature, a striking member secured to and movable with said armature and having an abutment on one side thereof and an extension on the other side thereof, a pivoted mass having a recessed surface opposite said extension, an abutment opposite said abutment on said striking member, said abutment on said mass being in

the path of movement of said striking member when said striking member is moved by shock for transferring the energy from said member to said mass, said extension on said striking member being in the path of movement of said mass, said mass transferring energy to said striking member to operate said striking member in the opposite direction from its original direction of movement.
